ELECTRONIC GUITAR

James D. Webster, Northport, N.Y., assignor to The
Fred. Gretsch Mfg. Co., Brooklyn, N.Y., a corporation
of New York

Filed May 16, 1963, Ser. No. 74,922

Term of patent 14 years

(Cl. D56—1)

Fig. 1.

Fig. 2.

Fig. 3.

Fig. 4.

FIG. 1 is a front plan view of an electronic guitar showing my new design;

FIG. 2 is a side elevational view;

FIG. 3 is a rear plan view; and

FIG. 4 is an end view looking to the right of FIG. 2, thereof.

The broken line showing of the guitar in FIGS. 1 to 4 is for illustrative purposes only.

The dominant features of my design reside in the portion shown in full lines.

This application is a continuation-in-part of my co-pending application Serial No. D. 67,393, filed November 6, 1961, and now abandoned.

I claim:

The ornamental design for an electronic guitar, substantially as shown and described.
